UNITED STATES PATENT OFFICE.

LESTER F. BIRD, OF SEATTLE, WASHINGTON.

INSULATION MOUNTING.

Application filed February 25, 1921. Serial No. 447,724.

To all whom it may concern:

Be it known that I, LESTER F. BIRD, citizen of the United States, residing at Seattle, in the county of King and State of Washington, have invented certain new and useful Improvements in Insulation Mountings, of which the following is a specification.

This invention relates to insulation mounting and is particularly directed to insulation mounting for winding of low capacity and low inductance electrical resistance.

An object of the invention is to provide a simplified form of insulation mounting for low capacity and low inductance resistances and in the form of a unit, for the purpose of simplification of assembly, inspection and replacement.

In accordance with the most preferred form of the invention, the wiring constituting the low capacity or low inductance, or both, is wound on a suitable substantially rigid insulating support, such as insulation fibre, board, micarto board or the like, such rigid insulating support being notched at correspondingly opposite locations along the lateral edges and the electrical wire threaded through such notches to present substantially parallel lengths of the wire on one face of the support, the connecting lengths of the wire being passed from one notch to the succeeding notch and on the opposite face of the support.

Further features and objects of the invention will be more fully understood from the following detailed description and the accompanying drawings, in which—

Fig. 1 is a front elevation of the preferred form of the invention; and

Fig. 2 is a side elevation of the same.

Referring to the drawings, the support 1 is of any suitable substantially rigid insulating material, such as a sheet of insulation fibre, insulation board, micarto board, or the like. For usual purposes, such support 15 is substantially rectangular in contour. Along the lower lateral edge, 2, is provided notches 3, 3, and along the upper lateral edge 4 are provided the similar notches 5, 5, the corresponding notches of the opposite edges being in alignment. Preferably, such notches 3, 5 are disposed respectively at equal distances from either end edge 6, 7, of the support 1. Such notches may be stamped in when dieing out the support 1 or may be cut into the formed support.

Adjacent the end 6 is provided the perforation 8 through which is threaded one end 9 of the wire and similarly adjacent the end 7 of the support 1 is provided the perforation 10 through which is threaded the opposite end 11 of the wire.

At the end 9 of the wire, the wire is passed for a relatively short portion 12 along the rear face of the support 1, then through the first upper notch 5, then downwardly for 65 a relatively long portion 13 along the front face of the support 1; then through the first lower notch 3, then for a relatively short portion 14 on the rear face of the support 1 and through the next lower notch 3; 70 then for a relatively short portion 12 along the rear face of the support 1, and containing similarly as aforesaid through pairs of notches alternatively at the upper and lower lateral edges to provide a series of relatively 75 long portions arranged substantially parallel to one another on one face of the support until the other end 11 of the wire passing through the other opening 10.

The support 1 may be provided with a 30 mounting bracket 17, preferably extending on the rear face of the support, which mounting bracket 17 serves also to stiffen the fibre, board or the like constituting the support, against any tendency of the wound 35 wire portions to collapse the fibre or board. As shown, each bracket 17 consists of a rectilinear body portion and end lugs or end portions bent at right angles to the body portion, such end lugs or end bent portions 90 being inserted in suitable openings in the support 1 either in snug fit therewith or held therein by swaging or otherwise. The effective lengths of the end lugs or bent end portions are sufficiently long to position the body portion of each bracket 17 95 beyond the wire portions 12, 14, disposed on the rear face of the support 1 as aforesaid, to guard against short circuiting and to provide an air closure for proper cooling of 100 such portions of the resistance wire.

From the above it will be noted that the major portions of the wire are aligned substantially wholly on one face of the insulation support, to facilitate inspection in the 105 event of breakage and to provide for proper cooling, as such face of the support is usually positioned to be exposed to cooling.

The invention also provides a mounting for resistance in the form of a unit which 110

can be readily positioned and readily removed for the purpose of inspection and replacement if necessary.

This form of mounting for electrical wiring is particularly adapted for low capacity resistance, low inductance resistance and similar electrical resistance wiring.

Whereas I have described my invention by reference to specific forms thereof, it will be understood that many changes and modifications may be made without departing from the spirit of the invention, as defined by the appended claim.

I claim.

15 An electrical resistance unit comprising a base of insulation material provided with

a series of notches arranged at uniform distances from one another at one lateral edge of said base and with a series of notches arranged at uniform distances from one another at the opposite edge of said base, said base being further provided with end perforations, an electrical wire having its opposite ends threaded through said perforations and its intermediate portion threaded successively through pairs of said notches at the opposite edges alternatively, and stiffening and supporting means for said base.

In testimony whereof I have affixed my signature.

LESTER F. BIRD.
